RICHARD BEAUMONT THOMAS, OF LONDON, ENGLAND, HUBERT SPENCE THOMAS, OF LLANDAFF, AND WILLIAM ROBERT DAVIES, OF WHITCHURCH, WALES; NORA CONSTANCE BEAUMONT THOMAS, HENRY ROBERT WILLIAM ANDERSON, AND CHARLES BATHURST ADMINISTRATORS OF SAID RICHARD BEAUMONT THOMAS, DECEASED.

APPARATUS FOR MANIPULATING METALLIC ARTICLES.

1,252,198.

Specification of Letters Patent. Patented Jan. 1, 1918.

Application filed June 20, 1914. Serial No. 846,305.

To all whom it may concern:

Be it known that we, RICHARD BEAUMONT THOMAS, HUBERT SPENCE THOMAS, and WILLIAM ROBERT DAVIES, subjects of the King of Great Britain, residing, respectively, at No. 39 Hyde Park Gate, London, S. W., England; "Hazelwood," Cardiff Road, Llandaff, Glamorganshire, Wales, and "Forest Lyn," Heoldon, Whitchurch, Glamorganshire, Wales, have invented certain new and useful Improvements in Apparatus for Manipulating Metallic Articles, of which the following is a specification.

Our invention relates to appliances or machinery in which a sucker device is employed for the manipulation of metallic plates, sheets, bars and the like and consists of the improvements hereinafter described in the said appliances or machinery whereby a regularity in the picking up of the plates or sheets singly or one by one is obtained unattainable by appliances or machinery as heretofore proposed.

Our invention is especially useful in connection with the manipulation of metallic plates and sheets in tin plate manufacture and we will describe the same in connection with such manufacture but we wish it to be understood that the said appliances or machinery may be employed generally where it is desired to pick up plates, sheets, bars or the like one by one for the purpose of feeding them to rolls, grippers or other devices to which the plates, sheets or the like are to be transferred, or for other purposes, for example the turning over of plates or sheets for examination and assortment of the same. Where the plates, sheets or bars are to be fed to rolls or the like we preferably arrange the stack or pile of plates, sheets or bars on a curved block and to reduce suction between contacting plates or sheets in a pile to a minimum and insure regularity in the picking up of the plates singly or one by one, we introduce between the presented or contacting surfaces of the plates sand or the like, or we deliver a blast of air or other blast against one or more edges of the plates or sheets, the air or other blast being preferably so directed as to tend to lift the outermost or uppermost plate, sheet or bar from the rest of the plates,

sheets or bars in the pile. We arrange the sucker device at one end of a lever or swinging arm by the action of which the sucker device is brought with such pressure on to the outermost or uppermost plate, sheet or bar that the sucker device affixes itself or adheres to the plate sheet, or bar with sufficient force to effect, on the motion of the arm or lever, the picking up and removal of the uppermost or outermost plate, sheet or bar from the pile. The lever may have in some part of its length a spring by which a yielding pressure is applied to the sucker or the like when the same is brought against or on to the plate, sheet or bar, or a spring or springs may be arranged if thought necessary or desirable between the sucker or lifting device and the connection of the same with the free end of the swinging arm. Where the plates, sheets or bars are to be turned over or reversed the lever or swinging arm is arranged to move through an angle of about 180 degrees, which motion may be effected through gearing operated through a shaft or an appropriate part of the machine.

The operation of the lever or arm lifts a plate, sheet or bar and brings it on to an inclined table or chute, the plate or the like being stripped from the sucker by the continued motion of the arm which passes through a slot in the table or chute and preferably brings the sucker under water by which it is wetted prior to being brought on to the next plate, sheet or bar. A part of the inclined table or chute down which the plates descend may have the form of a counterpoised lever so that should more than one plate at a time be lifted and passed on to the jointed part of the table or chute, the jointed part of the table or chute will turn on its pivot and permit the plates, sheets or bars to slide therefrom under the table or chute and prevent their delivery to the rolls or other machinery and thus obviate damage which might result to the said rolls or machinery adjusted for the treatment of the plates, sheets or bars singly or one at a time.

An alarm, for example an electric bell or lamp or both may be employed to indicate when the jointed portion of the table or chute has turned under the weight of more

than one plate, sheet or bar and deposited the said plates, sheets or bars under the table or chute.

Figure 1 of the accompanying drawing 5 represents in side elevation the appliance or machine for feeding metallic plates or sheets constituting our invention as arranged for feeding plates or sheets to tinning machines.

Fig. 2 is a plan of the same showing a 10 series of three of the sheet feeding appliances.

Fig. 3 represents in elevation drawn to a larger scale a modified sucker and parts adjacent thereto.

15 Fig. 4 is a view similar to Fig. 1 showing the machine equipped with the modified sucker shown in Fig. 3.

The same letters of reference indicate the 20 same parts in the several figures of the drawing.

a is the hollow conical cup preferably of india rubber constituting the sucker proper the said sucker a being carried by a pin b occupying an eye at the end of the long arm 25 of the lever c a coiled spring d being arranged between the sucker and the end of the long arm of the lever c. Preferably a series of the levers c is fixed on a rocking shaft c¹ and by the oscillation or backward 30 and forward partial rotation of the said shaft the levers receive an oscillating motion through about 180 degrees. The long arms of the levers c are counterbalanced by the weighted short arms c². By the action of 35 the levers a single plate is lifted and carried over on to the chute e which consists of a series of lazy disk rolls the axes of which are supported by inclined bars e¹ the inclination of the bars being seen in Fig. 1. As soon as 40 the sucker is released from the plate or sheet by the continued motion of the levers between and below the bars e¹ the plate or sheet travels down the chute and falls on to the preferably somewhat lower inclined 45 chute e² which has the form of a counterbalanced lever with adjustable weights e³.

The levers e² are pivoted on knife edge supports f (or their equivalents) and the counterbalanced weights e³ are adjusted so 50 that should more than a single plate be received on them simultaneously the lever e² will turn on its pivot and pass the said two or more plates or sheets under the table of the machine. If a single plate only is received by the levers e² it passes down the chute to the rolls or other appliances by which it is to be received. The oscillation of the shaft c¹ through the desired angle 55 may be effected in various ways. In the drawing we have shown the said shaft operated by spur wheel gearing, c³ being a pinion on the shaft c¹ in gear with a spur wheel g¹ on a spindle g arranged parallel with the said shaft. The spur wheel g¹ receives its 60 backward and forward turning motion from

the pulley driven, or otherwise driven, shaft h through the crank i and connecting rod k the said connecting rod k having a preferably adjustable connection with the lever arm g² carried by the spur wheel g¹ or its spindle g.

Preferably the sucker a is carried below the chute e and there wetted previous to the next operation. An example of a suitable wetting device for the sucker is shown in 75 Fig. 4, it consisting of a jet 2 attached to a water supply pipe 3. With this arrangement, when the arm c is at or near its lowest position, the cup a is brought under a stream of water issuing from the jet 2 whereby the 80 cup is wetted, the surplus water running from the cup when the arm c swings to its opposite position to bring the cup a onto the next sheet to be picked up and transferred to the chute. Also the sucker may be provided with a valve a¹ as is represented in 85 Figs. 3 and 4 the axial rod a² of which is kept down on its seat by the coiled spring a³. A trip lever m is provided to effect the lifting of the valve a¹ off its seat when the 90 plate or sheet reaches the chute e the trip lever m for each cup being actuated automatically by a projection n arranged in its path. On the lifting of the valve air is admitted to the sucker and the plate or sheet 95 is instantly released.

If desired we may obtain a vacuum or partial vacuum in the sucker, by the action of a pump.

We wish it to be understood that we do not 100 limit ourselves to the precise construction and arrangement of parts hereinbefore described and illustrated in the accompanying drawings as the operating mechanism may be varied within considerable limits 105 without departing from the nature of our invention.

We claim:—

1. Mechanism for removing sheets one by one from a stack comprising, in combination, a journaled arm provided with an elastic cup the edge of which, by the motion of the arm in one direction, is brought onto the uppermost sheet in the stack and is spread out flat or approximately flat under the pressure of the arm so that on the reverse motion of said arm atmospheric pressure alone causes the cup to act as a sucker on the uppermost sheet which is thus picked up and removed from the stacked sheets, means for wetting the edge of the cup prior to the engagement with each sheet, and means for moving the journaled arm.

2. In mechanism for manipulating stacked sheets and removing the sheets one by one 125 from the stack, the combination of means comprising an arm secured to a horizontal rocking shaft, the said arm performing an oscillatory or swinging motion in a vertical plane, the free end of the arm carrying an 130

- elastic cup the edge of which is by the oscillatory or swinging motion of the arm in one direction brought onto the uppermost sheet in the stack, the cup being thereby flattened or spread out so that on the arm commencing its reverse swinging motion atmospheric pressure acting on the flattened or spread-out cup and sheet causes the said uppermost sheet to adhere to the cup and to be carried over by the swinging motion of the arm to the other side of the shaft, and a chute embodying bars between which the arm and cup pass and to which the sheet is thereby transferred.
3. In mechanism for manipulating stacked sheets and removing the sheets one by one from the stack, the combination of means comprising an arm capable of a swinging motion in a vertical plane, the free end of the arm carrying an elastic cup capable of being spread out or flattened when brought by the arm onto the uppermost sheet in the stack, means for wetting the cup before being brought into contact with the uppermost sheet, so that on the arm commencing a reverse motion atmospheric pressure acting between the flattened or spread out cup and sheet causes the sheet to be lifted and transferred to an inclined chute, and means for detaching the sheet from the arm, said means consisting of a spring-closed valve in the cup and a coöperating valve-opening member.
4. In mechanism for manipulating stacked
- sheets and removing the sheets one by one 35 from the stack, the combination of means comprising an arm fixed on a rocking shaft and having on its free end an elastic cup having a suction releasing valve and an actuating lever for said valve, said arm and cup receiving an overthrow swinging motion due to the forward and backward partial rotation of the said shaft, the elastic cup at the end of the swinging of the arm in one direction being brought onto the uppermost sheet in the stack on which it is flattened or spread out so that on the arm commencing its reverse motion atmospheric pressure causes the sheet to adhere to the cup and to be picked up and carried over, a chute 50 embodying bars between which the arm and cup pass and to which the sheet is transferred, and a support or pressure bar below the chute with which the valve-opening lever carried by the swinging arm is made to contact and thereby effect the opening of the valve in the cup and the release of the suction in the cup by the time the sheet reaches or nearly reaches the surface of the chute.
- In testimony whereof we have hereunto 60 set our hands in presence of two subscribing witnesses.
